Inventor:
James W. Suporter
Munday, Clarke & Aspinwall Atto:

UNITED STATES PATENT OFFICE.

JULES H. VENON, OF NEW YORK, N. Y.

DESIGN FOR A VASE OR SIMILAR ARTICLE.

Application filed December 13, 1923. Serial No. 8,021. Term of patent 7 years.

To all whom it may concern:

Be it known that I, JULES H. VENON, a citizen of the United States, and resident of the city, county, and State of New York, have invented a new, original, and ornamental Design for a Vase or Similar Article of Ornamental Glassware, of which the following is a specification, reference being had to the accompanying drawing, forming part thereof.

In the drawing is shown, in elevation, a vase of fancy ornamental glassware, showing my new design embodied therein.

The important feature of the design is the combined optical effect produced by the numerous spirally curving surfaces.

I claim:

The ornamental design for a vase or similar article, as shown and described.

J. H. VENON.
